UNITED STATES PATENT OFFICE.

GEORGE T. TRUNDLE, JR., OF CLEVELAND, OHIO, ASSIGNOR TO THE AMERICAN MULTIGRAPH COMPANY, OF CLEVELAND, OHIO, A CORPORATION OF OHIO.

RULE FOR ROTARY PRINTING-MACHINES.

1,109,374.

Specification of Letters Patent.

Patented Sept. 1, 1914.

Application filed December 2, 1912. Serial No. 734,438.

To all whom it may concern:

Be it known that I, GEORGE T. TRUNDLE, Jr., a citizen of the United States, residing at Cleveland, in the county of Cuyahoga and State of Ohio, have invented a certain new and useful Improvement in Rules for Rotary Printing-Machines, of which the following is a full, clear, and exact description, reference being had to the accompanying drawings.

The object of this invention is to provide an effective column rule for short type assembled in a suitable holder.

More particularly the invention relates to rules adapted for mounting on a member having rails and overhanging edges which hold between them grooved type.

The invention is especially well adapted for use with Multigraph type of the form shown in Patent No. 836,026, and may be very conveniently employed when such type are mounted on a drum or segment rigidly carrying rails, like the structures shown in patent Reissue No. 12,622 or No. 993,495, for example.

My column rule, briefly, comprises a strip, preferably of metal adapted to extend across various rails and rest on them and extend type high above them, the strip having tongues which project into spaces between rails and are provided with means to effectively engage the type. To accomplish this, the tongues are preferably bent laterally to extend beneath a portion of the type, where-by the rail is firmly held on the typeholder. Some of the tongues are preferably bent in one direction and others in the other direction to engage beneath type on either side of the rail in different channels. Accordingly, when the type are held against spreading longitudinally the rule is effectively locked in place. When the type have beveled feet, after the manner of Multigraph type, shown in Patent No. 836,026, the bent ends of the rule tongues are preferably at an angle corresponding to the bevel of the foot of the type.

It will be seen that such a rule as described may be put in place after the matter to be printed has been assembled on the drum or holder, it being simply necessary to separate the lines slightly where the rule is to go, then insert the rule, and then com-

press the lines against the rule and block their ends by suitable fastening devices. 55

The invention is illustrated in the drawings hereof and is hereinafter more fully described and the essential characteristics set out in the claims.

In the drawings, Figure 1 is a side elevation of one of my rules adapted for mounting on a curved segment or drum; Fig. 2 is a perspective view of a portion of such segment or drum having three of my column rules mounted thereon with type between them; Figs. 3 and 4 are enlarged cross sections through my rule taken at adjacent tongues and showing the bent ends of the tongues in conjunction with type held by the rails; Fig. 5 is a similar view showing 70 my rule with flat-bottomed type.

Referring by letters to the parts shown in the drawing, A represents the arcual body portion of my rule, the radial dimension of which is considerably greater than the thickness of the printing edge, so that my rule may be said to stand on edge. Projecting from the supporting edge of the rule are radial tongues normal to the printing surface of the rule, and, for a distance, lying 80 in the plane of the rule. The free end portions of these tongues are bent preferably first in one direction, as shown at a' and then in the opposite direction, as shown at a'' . The angle which these bends make to 85 the rest of the tongues depends on the style of type with which the rule is to be used; in Figs. 1, 2 and 3 the angle is oblique because the type has a beveled foot, while in Fig. 2 the extension a^3 is at a right angle to 90 coöperate with type having a flat bottom.

B represents the body of a rotary drum or segment having parallel rails b with overhanging edges. These rails may conveniently be of an I-shape in cross section set 95 into grooves in the body of the segment or drum. The overhanging edges b' of such rails leave grooves b^2 in the sides of the rails between the edges and the holding body. The rails, with such body, constitute 100 the typeholder referred to.

C indicates the type. These are shown as short members having grooves c in their opposite sides by which they are loosely held between adjacent rails. The ribs or edges 105 b^3 of the rails occupy the grooves of the

type and the feet of the type extend into the grooves b^2 of the rails and the head portion of the type overhang the top of the rails, as will be well understood. The type are shown in Figs. 3 and 4 as having transversely beveled feet c' , and in Fig. 5 as having a flat bottom c^2 .

The matter to be arranged in columns is assembled on the holder in the usual manner. Then it is separated a short distance where the column rule is to go and the rule inserted at this place with the tongues projecting into the space between the rail heads b' . In this position some of the bent ends a' of the tongues will extend beneath the foot of the type in the assembled matter. Then the adjacent portions of the type lines on the opposite side of the rule are shoved against the rule, thus coming over the other projecting tongues a^2 . In this manner the rule is effectively held in place. To enable the rule to be easily installed in the drum without unduly springing it, I may make the tongues materially narrower than the openings between the typeholding rails, or I may taper the edges of the tongues toward the center of the drum, as shown in Fig. 1.

If there is to be a rule at the extreme edge of the type-matter, this may be effectively held on the unprinting side by mounting quads or spaces against it and blocking them by suitable line lock clips, as, for example, the clip shown at D in Fig. 2 and made in accordance with Patent No. 35 1,031,447.

It will be seen that my column rule is very cheap and simple in construction; is easily put in place and removed when desired, and, when in place, effectively prints the column line.

The rules may be made in various lengths for various columns, or in comparatively long lengths from which sections are cut off to suit the matter being printed.

It may be noted that, for claims on the broad idea of a column rule having inwardly projecting tongues of various forms, reference should be made to my copending application No. 845,756, filed June 18, 1914 and to the copending applications of Harry C. Gammeter, No. 780,159, filed July 21st, 1913 and of Samuel A. Neidich, No. 760,228, filed April 10th, 1913 and No. 776,531, filed June 30th, 1913—all of said applications being assigned to my assignee, The American Multigraph Company. The present application is concerned primarily with the feature of holding the column rule against movement by having portions of the rule extending beneath portions of the adjacent type.

Having thus described my invention, what I claim is:

1. A column rule consisting of a strip having a tongue projecting from the support-

ing edge in a direction normal to the printing edge, the lower portion of said tongue being bent at an angle to the plane of the strip.

2. A column rule consisting of an arcual strip having radial tongues projecting from the concave edge, the inner portions of said tongues being bent at an angle to the plane of the strip. 70

3. A column rule consisting of a strip having tongues projecting downwardly from the bottom edge, the tongues near their ends being bent, one toward one side of the strip and another toward the opposite side of the strip. 75

4. A column rule consisting of a strip, a series of tongues projecting downwardly from the bottom edge of the strip, said tongues for a distance lying in the plane of the strip and then adjacent to their free ends being bent at an angle to the plane of the strip. 80

5. A column rule consisting of an arcual strip, radial tongues projecting from the concave edge of the strip, said tongues for a distance lying in the plane of the strip and then adjacent to their free ends being bent at an angle to the plane of the strip. 90

6. A column rule consisting of a strip, a series of tongues projecting from the bottom edge of the strip, said tongues adjacent to their free ends being bent at an angle to the plane of the strip, alternate bends being in the opposite direction. 95

7. The combination, with grooved type and a holder therefor having overhanging rails, of a column rule adapted to be mounted on the face of such holder between type in lines, and means on the rule to engage beneath the type, whereby retention is provided in addition to the frictional grasp of the type line for holding the rule in place. 100

8. The combination, with grooved type and a holder therefor having overhanging rails, of a column rule adapted to be mounted on the face of such holder between type in lines, and tongues extending from the strip and spaced to enter channels between rails, the inner portions of the tongues being bent at an angle to the plane of the strip. 105

9. The combination, with a holder for type consisting of parallel overhanging rails rigidly held together and type mounted between said rails grooved on its opposite sides and having beveled feet, of a column rule adapted to extend crosswise of the rails and rest on the outer surface thereof, said rule having tongues extending inward between adjacent type in lines, said tongue adjacent to the strip being in the same plane as the strip, the inner portion of the tongue being bent at an oblique angle to such plane to lie closely against the beveled foot of adjacent type. 110

10. The combination, with a segmental, 115

120

125

holder for type consisting of parallel overhanging rails rigidly held equi-distant about an axis, and type mounted between said rails grooved on its opposite side and having beveled feet, of a column rule adapted to extend crosswise of the rails and rest on the outer surface thereof, said rule having tongues extending radially inward into the channels between rails, said tongue adjacent to the strip being in the same plane as the strip, the inner portion of the tongue being bent at an oblique angle to such plane.

11. The combination of a railed holder, grooved type having transversely beveled feet, and a column rule having inwardly projecting tongues, the end portions of which are bent at an oblique angle alternately in opposite directions.

12. The combination, with a typeholder consisting of parallel rails with overhanging edges rigidly held equi-distantly about an axis, of a column rule for use on said holder comprising an arcual strip having inwardly projecting radial tongues, the inner portions of such tongues being bent at an angle to the plane of the rest of the tongues and of the strip.

13. The combination, with a holder for type consisting of parallel rails with overhanging edges held in rigid relation to each other equi-distantly about an axis and type grooved on its opposite sides and mounted between adjacent rails, said type having transversely beveled feet, of a column rule mounted on the face of such rails and extending transversely thereof and consisting of a strip, the height of which corresponds to the height of the head and character of the type, and radial tongues extending inwardly from the concave edge of the strip, said tongues lying in the plane of the strip for a distance substantially equal to the depth of the rail head, the extreme portions of the tongues being bent at an oblique angle to the rest of the tongue and the body of the strip, said oblique angle being substantially the angle of the beveled foot of the type, said bent portions of alternate tongues extending from opposite sides of the strip.

14. A rule comprising a strip having a printing edge, and tongues projecting in a direction normal to the printing edge from intermediate portions of the opposite edge thereof, the end portions of the tongues being bent at oblique angles to the plane of the strip.

15. A rule comprising an arcual strip, and tongues projecting radially from the concave edge thereof, the end portions of said tongues being bent at oblique angles to the plane of the strip.

16. A rule comprising an arcual strip, having tongues projecting in a radial direction from the concave edge of the strip, said

tongues having their edges tapered toward points nearer than the center of the arc.

17. A rule comprising an arcual strip, having tongues projecting in a radial direction from the concave edge of the strip, said tongues having their edges tapered toward points nearer than the center of the arc and having their end portions bent at an angle to the plane of the strip.

18. As a new article of manufacture, a column rule made from a single piece of sheet metal and consisting of a strip having tongues projecting in the plane of the strip from the bottom edge thereof, the tongues being bent near their free ends at angles to such plane.

19. As a new article of manufacture, a column rule made from a single piece of sheet metal and consisting of a curved strip having radial tongues projecting in the plane of the strip from the concave edge thereof, the tongues being bent near their free ends at oblique angles to such plane.

20. A column rule adapted to stand on edge and having tongues projecting from its supporting edge and adapted to stand between types in lines extending transversely of the rule, said tongues having flanges projecting from the plane of the rest of the tongues.

21. A column rule consisting of a curved strip having tongues projecting from the concave edge normal to the active edge of the strip and tapered inwardly to make them more pointed than if their edges were radial.

22. A column rule consisting of an arcual strip having tongues projecting radially inward from various intermediate points of the supporting edge, the lower portions of said tongues extending at an angle to the plane of the strip.

23. A column rule consisting of an arcual strip having radial tongues projecting from the concave edge, the inner portions of said tongues being bent at an angle to the plane of the strip.

24. In a duplicating machine, the combination with a rotary printing drum having a plurality of undercut channels in its periphery, a type having flanges fitted in said channels; and, a rule strip having a printing surface curved in concentric relation with said drum, held between said flanged type, having lugs extending into said channels and provided at their inner ends with flanges extending beneath the feet of adjacent type in the channel.

25. In a duplicating machine, the combination, with a rotary printing drum having a plurality of undercut channels in its periphery, of type having flanges fitted in said channels, and a rule strip having a printing surface curved in concentric relation with

said drum having means connecting it with said type independently of said drum.

26. A column rule consisting of a curved strip having a tongue projecting from the concave edge, a lower portion of the tongue extending at an angle to the plane of the portion of the strip which carries it.

Copies of this patent may be obtained for five cents each, by addressing the "Commissioner of Patents, Washington, D. C."

In testimony whereof, I hereunto affix my signature in the presence of two witnesses.
